BOBBY PIN DISPENSERS AND REFILLING MEANS

Philip A. Avelli, Ozone Park, N. Y.

Application November 7, 1952, Serial No. 319,349

8 Claims. (Cl. 132—1)

The present invention relates to new and useful improvements in a bobby pin dispenser and more especially, the present invention proposes certain improvements in the bobby pin dispensers disclosed in my prior U. S. 15 Patents Nos. 2,477,034 and 2,539,684.

As in the case of those prior patents, the present invention has as its primary purpose the construction of a novel dispenser for supporting bobby pins in a stack and from which the bobby pins can be dispensed one at a time with their tines spread so that the ejected pins can be conveniently taken from the dispenser with the tines spread to be inserted in the hair which is being held in a curled formation with the other hand. However, the present invention proposes certain improvements in the construction of the dispenser to make it adjustable to accommodate bobby pins of different lengths while at the same time making the dispenser much simpler to reload, using the cardboards upon which bobby pins are usually arranged for sale to the public.

To accomplish the first of the objects of the present invention, it is proposed to provide a receptacle forming a magazine for a stack of bobby pins which has a rear wall and a fixed end wall along one vertical edge thereof and a movable end wall along the other vertical edge thereof arranged in a manner so that the position of the movable end wall can be adjusted with relation to the fixed end wall to receive between them bobby pins of different lengths.

In packaging the conventional bobby pins for sale, it is common practice to slip them into position upon the edge of a cardboard with the bight portion of the pins extending about the edge of the cardboard. It is an object of the present invention to arrange the bobby pins in position on such a cardboard retainer in groups each having a sufficient number of pins to completely fill the dispenser; with perforations dividing off the groups of pins to be torn from the whole cardboard retainer, in a manner to be slipped into position in the dispenser without having to remove the bobby pins therefrom.

Still further, the present invention proposes providing the fixed end wall of the receptacle with a vertically extended slot which opens to the top end thereof in a manner so that the torn away portion of the cardboard together with its group of bobby pins can be inserted into the receptacle from the top thereof with the end of the portion of cardboard which projects from the free ends of the tines of the bobby pins projecting through the slot, leaving the portion of cardboard to be withdrawn through the slot after all of the pins of the group are in position within the receptacle.

It is a further object of the present invention to construct an improved bobby pin dispenser which is simple and durable, which can be manufactured and sold at a reasonable cost and which is effective for its intended purposes.

For further comprehension of the invention, and of the objects and advantages thereof, reference will be had to the following description and accompanying drawings, and to the appended claims in which the various novel features of the invention are more particularly set forth.

2

On the accompanying drawings forming a material part of this disclosure:

Fig. 1 is a front elevational view of the bobby pin dispenser constructed in accordance with the present invention.

Fig. 2 is an end elevational view looking in the direction of the line 2—2 of Fig. 1.

Fig. 3 is a bottom plan view of Fig. 1.

Fig. 4 is a view similar to Fig. 1, but with the front cover lowered to its open position.

Fig. 5 is an enlarged partial vertical sectional view taken substantially on the line 5—5 of Fig. 1.

Fig. 6 is an enlarged horizontal sectional view taken on the line 6—6 of Fig. 1 and having a portion of the support bracket broken away.

Fig. 7 is a perspective view of the weight, per se.

Fig. 8 is another view similar to Fig. 1, but with the front wall and front cover completely removed and with a portion of the track and ejector broken away.

Fig. 9 is an enlarged partial horizontal sectional view taken substantially on the line 9—9 of Fig. 8.

Fig. 10 is an elevational view showing the cardboard mounting the groups of bobby pins for insertion into the dispenser.

Fig. 11 is a perspective view of the bobby pin dispenser constructed in accordance with a modification of the present invention.

Fig. 12 is a front elevational view of Fig. 11 with the bottom right-hand corner broken away to reveal interior constructions.

Fig. 13 is an enlarged transverse sectional view taken on the line 13—13 of Fig. 12.

Fig. 14 is an enlarged partial vertical sectional view taken substantially on the line 14—14 of Fig. 12.

Fig. 15 is an inside perspective view of the cover used in the form of the invention shown in Figs. 11 to 14.

Fig. 16 is a perspective view of the bobby pin dispenser constructed in accordance with a still further modification of the present invention, with a corner broken away to show the interior structure thereof.

Fig. 17 is a view similar to Fig. 16 but showing the ejector in operative engagement with the vertically adjustable end wall.

Fig. 18 is a vertical sectional view taken along line 18—18 of Fig. 16.

Fig. 19 is a vertical sectional view taken along line 19—19 of Fig. 16.

Fig. 20 is a front elevational view of Fig. 16 with the bottom right hand corner broken away to reveal interior constructions.

Fig. 21 is a fragmentary perspective view of one of the parts of the modified form of the invention shown in Figs. 15 and 16 to 20.

The bobby pin dispenser, according to the present invention, includes a receptacle 20 which forms a magazine for a stack of bobby pins 21 which are to be dispensed one at a time with their tines spread, as best shown in Figs. 2 and 3. The receptacle 20 is constructed to include a rear wall 22 having along one vertical edge thereof a fixed end wall 23. In the present construction, the fixed end wall 23 is integrally formed with the rear wall 22 of metal or one of the synthetic resinous plastic materials. Along its inner edge and immediately adjacent the inner face of the rear wall 22, the fixed end wall 23 is formed with an integral ledge portion 23a. Forwardly of the ledge portion 23a, the fixed end wall 23 carries a fixed guide rail 24 which tapers in width toward its free end. The bobby pins 21 are stacked in the receptacle 20 in a position so that the free ends of the tines 21a of the pins are disposed along opposite faces of the guide rail 24, as clearly shown in Figs. 8 and 9. The location of the tines 21a on opposite

sides of the guide rail 24 serves to retain the pins 21 from turning on their longitudinal axis within the receptacle 20 and for a further purpose which will become clear as this description proceeds. The lower end of the fixed end wall 23, which is disposed above the bottom edge of the rear wall 22, continues in a wedge-shaped spreader 25 for spreading the tines 21^a of the bobby pins 21 as they are separately dispensed from the receptacle 20. The wedge-shaped formation of the spreader 25 is best shown in Fig. 3 from which the action of that spreader in opening the tines 21^a of the pins 21 is also apparent. As the inner thin edge of the spreader 25 continues upward along the inner edge of the fixed end wall 23 it forms the guide rail 24, compare Figs. 8 and 9. Therefore, in addition to holding the bobby pins 21 from turning, the guide rail 24 also functions to guide the bobby pins 21 into position with relation to the spreader 25.

A movable wall 26 is secured in position adjacent the other vertical side edge of the rear wall 22. The movable wall 26, formed of the same material as the rear wall 22 has along its inner edge and immediately adjacent the inner face of the rear wall 22 an integral ledge portion 26^a against which the bight portions of the bobby pins 21 are rested, as shown in Fig. 6. The movable wall 26 is adjustably secured in position on the rear wall 22 to be shifted parallelly relative to the fixed end wall 23 to adjust the receptacle to accommodate bobby pins 21 of different lengths. Adjustment of the movable wall 26 is accomplished by forming the rear wall 22 with vertically spaced elongated slots 27 through which screws 28 are turnably and slidably extended, see Fig. 6. The inner ends of the screws 28 are threaded into complementary threaded recesses 29 formed in the movable end wall 26. When the screws 28 are loosened, the position of the movable end wall 26 can be shifted horizontally to space that wall with relation to the fixed end wall 23 to receive the bobby pins 21 of the length which are to be inserted into the receptacle 20.

Secured in position on the bottom of the rear wall 22 at the bottom ends of the end walls 23 and 26, there is a track 30. The track 30 is formed of an elongated piece of metal and is secured to the rear wall 22 by means of screws 31, one of which is shown in Fig. 5. The track 30 is positioned with its one end spaced slightly from the inner edge of the fixed end wall 23 providing clearance for the bight portion of an ejected bobby pin 21 permitting the same to be slipped downward off the wedge-shaped spreader 25 when the fully ejected position is reached. The other end of the track 30 extends well beyond the outer face of the movable end wall 26 and the adjacent vertical edge of the rear wall 22.

A relatively low front wall 32 is removably secured to the adjacent face of the track 30 and the bottom end portion of the fixed end wall 23 by means of screws 33, see Figs. 1 and 5. The front wall 32 functions to close the lower portion of the receptacle 20. Pivottally attached to the top edge of the front wall 32, there is a cover 34 which closes the top portion of the receptacle. At its bottom edge, the cover 34 is formed with spaced depending lugs 35 which project into complementary cutouts 36 formed in the top edge of the front wall 32. The top edge of the front wall 32 and the lugs 35 are formed with aligned holes through which an elongated pin 37 is extended for pivotally retaining the cover 34 in position. It is appreciated, of course, that there is sufficient clearance between the adjacent edges of the front wall 32 and the cover 34 to permit pivotal movements of the cover. Along its top edge, the cover 34 continues in a rearwardly extended block portion 38 which hooks over the top ends of the end walls 23 and 26 and the top edge of the rear wall 22 for closing the top of the receptacle 20 and for holding the cover 34 in its closed position. The cover 34 may be integrally formed with the block portion 38 or, if desired, the block portion can be a separate strip secured in position along the top edge of the cover.

The bottom corner of the front wall 32 immediately in front of the wedge-shaped spreader 25 has a cutout 39. The cutout 39 provides clearance for the tine 21^a of the pin 21 being ejected, which is located immediately adjacent the inner face of the front wall 32, as shown in Fig. 3.

A support bracket 40 is provided for mounting the entire receptacle upon a wall bracket, not shown but similar in construction to that described in my prior U. S. Patent No. 2,477,034, mounted on a wall or other vertical surface so that the dispenser will be convenient for ejection of the bobby pins 21. The support bracket 40 comprises spaced metallic plates 41 which are secured to the side faces of the projecting other end portion of the track 30 by means of screws 42. The vertical edge portions of the plates 41 furthest removed from the receptacle 20 are bent into outwardly extended flanges 43 which continue at their top ends into downwardly faced hook portions 44. The flanges 43 are provided for insertion into the wall bracket and the hook portions 44 function to restrain the flanges 43 from slipping down out of the bottom of the wall bracket.

The track 30 is provided for slidably supporting an ejector 45 to be used for ejecting the bobby pins 21 one at a time. The ejector 45 comprises a main body portion 46 formed along its top with an upstanding tongue portion 47 which is slidably extended upward through an elongated slot 30^a formed in the track 30. The tongue portion 47 has its top face flush with the top face of the track 30. Secured to the top face of the tongue portion 47 there is an ejector strip 48 which is retained in position by several screws 49. The tongue portion 47 at the end adjacent the fixed end wall 23 has a portion which projects beyond the adjacent end of the ejector strip 48 forming a ledge 50 upon which the bight end of the lowermost bobby pin 21 rests, as clearly shown in Fig. 8. The free end portions of the tines 21^a of that lowermost bobby pin 21 rest on the end of the track 30 adjacent the fixed wall 23 also as shown in Fig. 8. The main body portion 46 at its end adjacent the fixed end wall 23 continues into a depending grip portion 51. The grip portion 51 permits the ejector 45 to be gripped in the fingers of one hand and slid along the track 30 until the end of the tongue portion 47 strikes the end of the track 30 immediately adjacent the fixed end wall 23. During such movement, the ejector strip 48 will push the lowermost bobby pin 21 outward beneath the bottom end of the fixed end wall 23 and past the wedge-shaped spreader 25. During such movement, the spreader 25 will function to spread the tines 21^a of the ejected pin 21, as shown in Figs. 1 to 3. When the fully extended position is reached, the bight portion will be located immediately adjacent the inner edge of the spreader 25 and the ejector 45 will then be free to be slid back to its starting position.

The serpentine formation of the one tine 21^a of the ejected pin 21 where it passes over the surface of the spreader 25 will hold the ejected pin in position until it is gripped with one hand, while holding the tines 21^a spread, and slipped off the bottom of the spreader 25. While still holding the tines 21^a spread, the removed pin is inserted into the curled hair which is being held in position by the other hand. By having the dispenser supported in position by the support bracket 40, the dispenser can be conveniently operated with one hand for dispensing the bobby pins 21 one at a time.

For lowering the stack of bobby pins 21 within the receptacle 20, each time a pin is removed and the ejector 45 is slid back to its starting position, a weight 52 is positioned within the receptacle 20, against the ledge portions 23^a and 26^a and rested on top of the stack of pins. At one end, the weight 52 is formed with a lip 53 which is engaged behind the guide rail 24, see Fig. 6, for insuring that the weight will be properly rested on top of the stack of bobby pins 21. The side of the weight 52 which faces the cover 34 is formed with a notch 54 by which a finger grip can be had on the weight for lifting it out

of the top of the receptacle 20 when the cover is pivoted to the open position shown in Fig. 4. The weight 52 has sufficient height so that the notch 54 will be located above the top edge of the front wall 32 when all of the bobby pins 21 are depleted from the interior of the receptacle.

The inner faces of the front wall 32 and the cover 34 are formed with end aligned vertically extended guide ribs 55 and 56 which project into the receptacle 20 and bear against the adjacent faces of the bobby pins 21, as best shown in Fig. 6, for insuring that those pins will be retained in the desired vertical stack. The ribs 55 are somewhat thicker than the ribs 56. To accommodate the ribs 55 and 56, the adjacent face of the weight 52 is formed with complementary grooves 57 and 58 into which the ribs extended to guide vertical sliding of the weight.

To facilitate positioning the stacks of bobby pins 21 within the receptacle 20, they are positioned on a cardboard 59 in groups of a sufficient number to fill the receptacle 20 and leave space above the stack for the insertion of the weight 52. To facilitate mounting the bobby pins 21 on the cardboard 59, see Fig. 10, the same is formed with end aligned spaced elongated slots 60. The bobby pins 21 are slipped into position on the cardboard 59 with their bight portions passing through the slots 60 and with their tines 21^a extending along opposite faces of the cardboard. Lines of perforations 61 extend from the ends of the slots 60 to the edges of the cardboard 59 adjacent the free ends of the tines 21^a dividing off portions 59^a of the cardboard 59, each carrying one group of the bobby pins 21.

The fixed wall 23 between the adjacent faces of the guide rail 24 and the ledge portion 23^a, is formed with a vertical slot 62 which opens through the top end of that wall. When the cover 34 is pivoted to the open position shown in Fig. 4 and the weight 52 is removed through the open top of the receptacle 20, the receptacle may then be furnished with a fresh stack of bobby pins 21. This is done by separating one of the portions 59^a from the main body of the cardboard 59 by tearing along the respective lines of perforations 61. The torn off portion 59^a is then gripped by the edge portion thereof which projects from the free ends of the tines 21^a and that portion 59^a is then slipped down into the open top of the slot 62, as shown in Fig. 8. That automatically stacks the group of bobby pins 21 within the receptacle 20 with the free ends of the tines 21^a extended along opposite sides of the guide rail 24, see Fig. 9. When the group of bobby pins 21 is completely lowered within the receptacle 20, the portion 59^a of the cardboard 59 is pulled out of the slot 62 leaving the stack of bobby pins 21 in position in the receptacle. The engagement of the free ends of the serpentine tines 21^a of the bobby pins 21 with the fixed end wall 23 will hold the bobby pins 21 from being pulled out of the receptacle 20 during removal of the portion 59^a of the cardboard 59. The weight 52 is then positioned on top of the fresh stock of bobby pins 21 and the cover 34 pivoted back to its closed position and the dispenser is then ready for individual ejection of the fresh supply of bobby pins 21.

If the new pins 21 are longer or shorter than the ones previously used in the dispenser, the same can be modified to accommodate the new length of pins by shifting the movable end wall 26 laterally with relation to the fixed end wall 23 to receive the longer or shorter pins. Weights 52 are supplied in several different lengths to be used with the walls 23 and 26 in their different adjusted positions; however, all of the weights 52 have the grooves 57 and 58 in the same position with relation to their lips 53 to receive the ribs 55 and 56.

To insure that the ejector 45 will always be stopped in the same position to receive the bight portions of the bobby pins 21 on the ledge 50 regardless of the length of the pins, the bottom end of the movable end wall 26 is formed with a depending stop member 63. The major portion of the top face of the ejector strip

48 is cut away forming a stop portion 64, see Fig. 8, at its end adjacent the fixed wall 23. On return movement of the ejector 45, the stop portion 64 engages the stop member 63 restraining the ejector 45 against further movement regardless of the positioning of the movable end wall 26 so that the ledge 50 will be in position to receive the bight portion of the next lowered bobby pin 21.

When the bobby pins 21 are to be restacked within the receptacle 20 for re-use, they can be engaged upon the edge portions of the removed portions 59^a of the cardboard 59 which can be saved for that purpose, or the pins 21 can be individually slipped into position within the receptacle through the open top thereof.

15 With the rear wall 22 formed of metal, it may, if desired, be slightly magnetized so as to attract the bobby pins 21 and hold them in the desired position against the ledge portions 23^a and 26^a of the end walls 23 and 26.

20 The modification of the invention shown in Figs. 11 to 15 is constructed to be hand held when operated and distinguishes from the prior form of the invention in the construction of the front wall 32' and in the construction of the ejector 45' for pushing the bobby pins 21 out past the spreader 25.

25 In the modification of the invention, the front wall 32' extends the full height of the receptacle 20' and is secured along its bottom edge to the track 30' and along its one vertical edge to the fixed end wall 23 by means of the screws 33. Extended down from its top edge,

30 the front wall 32' has a cutout 70 located substantially centrally of the width thereof and which has its bottom stopped some distance above the top face of the track 30'. Provided for closing the cutout 70, there is a cover 34' which is preferably molded of a transparent synthetic resinous material.

35 Along its vertical side edges, the cover 34' has beveled edges 71, see particularly Fig. 15, which engage complementary grooves 72 formed in the material of the front wall 32' defining the vertical side edges of the cutout 70. The inner face of the cover 34', at the top edge thereof, is formed with an inwardly

40 extended block portion 38' for closing the open top of the receptacle 20' between the end walls 23 and 26. The front face of the cover 34' is formed with a notch 73 by which a finger grip can be had on the cover for pulling it up out of the cutout 70.

45 The track 30' is of a length corresponding to slightly less than the width of the receptacle 20' and is mounted in position with its one end flush with the vertical edge of the rear wall 22' adjacent the adjustable end wall 26.

50 The other end of the track 30' is spaced from the spreader 25 for the same purpose as in the previous form of the invention. Intermediate of its ends, the track 30' has the elongated slot 30^a for slidably supporting the ejector 45'.

55 The ejector 45' consists of a main body portion 75 which has its top portion slidably engaging the slot 30^a and which is provided at its top end with an enlarged head 76 which slides on the top face of the track 30'.

60 The top corner of the head 76 facing the fixed end wall 23 is formed with a recess 77 for receiving the bight portion of the lowermost bobby pin 21 to push the same out of the receptacle 20', as the ejector 45' is moved from the left to the right as viewed in Figs. 11 and 12.

65 The bottom portion of the main body portion 75 projects from the bottom of the track 30' and has finger pieces 77' secured to the opposed faces thereof by means of a rivet 78. The tops of the finger pieces 77' ride along the bottom face of the track 30' holding the main body 75 from sliding upward within the track slot 30^a.

70 A leaf spring 80 is provided for holding the stack of bobby pins 21 in a raised position while the lowermost pin of the stack is being ejected by sliding movement of the ejector 45'. The spring 80 extends along the outer face of the movable end wall 26 and is se-

cured at its top end to that wall by several rivets 81. The bottom end of the spring 80 is bent into an inwardly extended retainer portion 82 which extends beneath the bight portion of the next lowermost bobby pin 21 while the ejector is in the process of ejecting the lowermost pin so as to retain the stack in its elevated position so as not to interfere with the return movement of the ejector following complete ejection of the lowermost bobby pin.

The retainer portion 82 continues into a depending tail portion 83, see Fig. 12, engaged behind the rear of the head 76 of the ejector 45' for causing the spring 80 to be flexed moving the retainer portion 82 out of the way when the ejector 45' is pushed completely to the right, as viewed in Fig. 12, so that the bight portion of the lowermost bobby pin 21 can drop into the recess 77 to be ejected on the next complete movement of the ejector toward the left. A similar arrangement of an ejector 45' and spring 80 is shown in my prior Patent No. 2,539,684.

In other respects, the form of the invention shown in Figs. 11 to 15 is similar to that described in connection with Figs. 1 to 10 and like reference numerals are used to identify like parts.

The further modification of the invention shown in Figs. 16 to 20 is constructed so as to be fully automatic with the ejector discharging the pins entirely from the dispenser, and distinguishes from the second form of the invention mainly in the construction of the end wall 23 and in a modification in the construction of the ejector 45' for pushing the bobby pins 21 out past the spreader 25.

In this further modification, the end wall 23 terminates at 34 and slidably abuts at this point a vertically adjustable end wall 23' consisting of a fixed upper portion 35 and a movable lower portion 36. The upper portion 35 is formed with the usual upper guide rail 37 and is provided with an internally threaded horizontal recess 38 adapted to receive a screw 39 whereby to secure the upper portion 35 to the front wall 32', and is further provided with a vertical cylindrical opening 40 for a purpose to be hereinafter described.

The lower portion 36 is formed with the usual lower guide rail 31 and at the bottom thereof with the usual spreader 25', and is further provided at the top thereof with an integral cylindrical extension 42 adapted to slidably engage the opening 40, as clearly shown in Fig. 18. Located within the opening 40, and intermediate the opening 40 and the cylindrical extension 42, is a helical spring 43, which normally urges the lower portion 36 into the position shown in Figs. 16, 18 and 20.

The bottom of the lower portion 36 is provided with a teat 34 having a lower inclined edge 35 and which is secured to the portion 36 by a shaft 36, the front 32' having a slot 37 to receive the shaft 36, the front 32' having a slot 37 to receive the shaft 36 and to permit vertical movement thereof.

The ejector 45' again consists of the main body portion 75 which has its top portion slidably engaging the slot 30' and which is provided at its top end with an enlarged head 76' having a horizontal recess 98 adapted to receive the shaft 99 of a finger 100 having an inclined upper edge 101 corresponding with the inclined lower edge 35. The front wall 32' is provided with a slot 102 to receive the shaft 99 and to permit horizontal movement thereof.

In operation of this form of the invention, the lower portion is normally maintained in the positions shown in Figs. 16, 18 and 20 by the spring 43, and the guide rail 31 and spreader 25' function in the same manner as the guide rails 24 and spreader 25 of the previous forms. As the ejector is moved from left to right, as shown in Fig. 17, the recess 77 receiving the bight portion of the lowermost bobby pin 21 pushes the same out of the receptacle 20'.

The upper edge 101 of the finger 100 slidably engages

the lower edge 35 of the teat 34 whereby to raise the latter vertically. This vertical movement is transmitted to the lower portion 36, thus raising the spreader 25' along therewith, which results in the automatic ejection of the pin from the dispenser, the upper edge 103 of the opening 39 acting as a shoulder against which the ejected pin abuts as the spreader 25' moves upwardly prior to complete ejection of the pin. As the ejector 45' returns to its original position shown in Fig. 16, the lower portion 36 returns to its lower position under the action of the spring 43, to await the next action of the ejector.

In other respects, the form of the invention shown in Figs. 16 to 21 is similar to that described in connection with Figs. 11 to 15 and like reference numerals are used to identify like parts.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A bobby pin dispenser, comprising a receptacle forming a magazine for a stack of bobby pins and having a rear wall integrally formed along one vertical edge thereof with a fixed end wall, a movable end wall adjustably mounted on said rear wall to be adjusted parallelly relative to said fixed end wall to accommodate bobby pins of different lengths, a track supported on said rear wall at a position slightly below said end walls, a low front wall support on said track and said fixed end wall with its lower edge flush with the lower edge of said rear wall, a cover hinged at its bottom edge on the top edge of said front wall, a wedge-shaped spreader formed at the bottom end of said fixed end wall, a guide rail on the inner vertical edge of said fixed end wall for guiding the free ends of the tines of the bobby pins into position on opposite sides of said spreader, and an ejector slidably mounted on said track for ejecting the lowermost bobby pin of the stack past said spreader so that said spreader functions to spread the tines of the ejected bobby pin.
2. A bobby pin dispenser, comprising a receptacle forming a magazine for a stack of bobby pins and having a rear wall integrally formed along one vertical edge thereof with a fixed end wall, a movable end wall adjustably mounted on said rear wall to be adjusted parallelly relative to said fixed end wall to accommodate bobby pins of different lengths, a track supported on said rear wall at a position slightly below said end walls, a low front wall supported on said track and said fixed end wall with its lower edge flush with the lower edge of said rear wall, a cover hinged at its bottom edge on the top edge of said front wall, a wedge-shaped spreader formed at the bottom end of said fixed end wall, a guide rail on the inner vertical edge of said fixed end wall for guiding the free ends of the tines of the bobby pins into position on opposite sides of said spreader, and an ejector slidably mounted on said track for ejecting the lowermost bobby pin of the stack past said spreader so that said spreader functions to spread the tines of the ejected bobby pin, and means for stopping said ejector in the proper position with relation to said movable end wall in all adjusted positions of that end wall.
3. A bobby pin dispenser, comprising a receptacle forming a magazine for a stack of bobby pins and having a rear wall integrally formed along one vertical edge thereof with a fixed end wall, a movable end wall adjustably mounted on said rear wall to be adjusted parallelly relative to said fixed end wall to accommodate bobby pins of different lengths, a track supported on said rear wall at a position slightly below said end walls, a low front wall supported on said track and said fixed

end wall with its lower edge flush with the lower edge of said rear wall, a cover hinged at its bottom edge on the top edge of said front wall, a wedge-shaped spreader formed at the bottom end of said fixed end wall, a guide rail on the inner vertical edge of said fixed end wall for guiding the free ends of the tines of the bobby pins into position on opposite sides of said spreader, and an ejector slidably mounted on said track for ejecting the lowermost bobby pin of the stack past said spreader so that said spreader functions to spread the tines of the ejected bobby pin, and means for stopping said ejector in the proper position with relation to said movable end wall in all adjusted positions of that end wall, said stopping means comprising a stop member depending from said movable end wall, and an upstanding stop portion on said ejector for engaging said stop member.

4. A bobby pin dispenser, comprising a receptacle forming a magazine for a stack of bobby pins and having a rear wall integrally formed along one vertical edge thereof with a fixed end wall, a movable end wall adjustably mounted on said rear wall to be adjusted parallelly relative to said fixed end wall to accommodate bobby pins of different lengths, a track supported on said rear wall at a position slightly below said end walls, a low front wall supported on said track and said fixed end wall with its lower edge flush with the lower edge of said rear wall, a cover hinged at its bottom edge of the top edge of said front wall, a wedge-shaped spreader formed at the bottom end of said fixed end wall, a guide rail on the inner vertical edge of said fixed end wall for guiding the free ends of the tines of the bobby pins into position on opposite sides of said spreader, and an ejector slidably mounted on said track for ejecting the lowermost bobby pin of the stack past said spreader so that said spreader functions to spread the tines of the ejected bobby pin, and means for stopping said ejector in the proper position with relation to said movable end wall in all adjusted positions of that end wall, said stopping means comprising a stop member depending from said movable end wall, and an upstanding stop portion on said ejector for engaging said stop member, said ejector having a grip portion extending from the bottom of said receptacle by which said ejector can be gripped to be manually slid for ejecting the lowermost bobby pin of the stack.

5. A bobby pin dispenser, comprising a receptacle forming a magazine for a stack of bobby pins and having a rear wall integrally formed along one vertical edge thereof with a fixed end wall, a movable end wall adjustably mounted on said rear wall to be adjusted parallelly relative to said fixed end wall to accommodate bobby pins of different lengths, a track supported on said rear wall at a position slightly below said end walls, a low front wall supported on said track and said fixed end wall with its lower edge flush with the lower edge of said rear wall, a cover hinged at its bottom edge on the top edge of said front wall, a wedge-shaped spreader formed at the bottom end of said fixed end wall, a guide rail on the inner vertical edge of said fixed end wall for guiding the free ends of the tines of the bobby pins into position on opposite sides of said spreader, and an ejector slidably mounted on said track for ejecting the lowermost bobby pin of the stack past said spreader so that said spreader functions to spread the tines of the ejected bobby pin, and bobby pins mounted upon removable cardboards in said receptacle in groups of a sufficient number to fill said receptacle, said cardboards having edge portions projecting outwardly of the receptacle for removal therefrom.

6. A bobby pin dispenser, comprising a receptacle forming a magazine for a stack of bobby pins and having a rear wall integrally formed along one vertical edge thereof with a fixed end wall, a movable end wall adjustably mounted on said rear wall to be adjusted parallelly relative to said fixed end wall to accommodate bobby pins of different lengths, a track supported on said rear wall at a position slightly below said end walls, a low

front wall supported on said track and said fixed end wall with its lower edge flush with the lower edge of said rear wall, a cover hinged at its bottom edge on the top edge of said front wall, a wedge-shaped spreader formed at the bottom end of said fixed end wall, a guide rail on the inner vertical edge of said fixed end wall for guiding the free ends of the tines of the bobby pins into position on opposite sides of said spreader, and an ejector slidably mounted on said track for ejecting the lowermost bobby pin of the stack past said spreader so that said spreader functions to spread the tines of the ejected bobby pin, and bobby pins mounted upon removable cardboards in said receptacle in groups of a sufficient number to fill said receptacle, said cardboards having edge portions projecting outwardly of the receptacle for removal therefrom, said fixed end wall rearward of said guide rail having a vertical slot opening through the top end thereof for receiving the bobby pins in position in the receptacle.

7. A bobby pin dispenser, comprising a receptacle forming a magazine for a stack of bobby pins and having a rear wall integrally formed along one vertical edge thereof with a fixed end wall, a movable end wall adjustably mounted on said rear wall to be adjusted parallelly relative to said fixed end wall to accommodate bobby pins of different lengths, a track supported on said rear wall at a position slightly below said end walls, a front wall supported on said track on said fixed end wall and closing at least a part of the respective side of said receptacle, a cover closing the remaining portion of that respective side of said receptacle, a wedge-shaped spreader formed at the bottom end of said fixed end wall, a guide rail on the inner vertical edge of said fixed end wall for guiding the free ends of the tines of the bobby pins into position on opposite sides of said spreader, and an ejector slidably mounted on said track for ejecting the lowermost bobby pin of the stack past said spreader so that said spreader functions to spread the tines of the ejected bobby pin.

8. A bobby pin dispenser, comprising a receptacle forming a magazine for a stack of bobby pins and having a rear wall integrally formed along one vertical edge thereof with a fixed end wall, a movable end wall adjustably mounted on said rear wall to be adjusted parallelly relative to said fixed end wall to accommodate bobby pins of different lengths, a track supported on said rear wall at a position slightly below said end walls, a front wall supported on said track and said fixed end wall and closing at least a part of the respective side of said receptacle, a cover closing the remaining portion of that respective side of said receptacle, a wedge-shaped spreader formed at the bottom end of said fixed end wall, a guide rail on the inner vertical edge of said fixed end wall for guiding the free ends of the tines of the bobby pins into position on opposite sides of said spreader, and an ejector slidably mounted on said track for ejecting the lowermost bobby pin of the stack past said spreader so that said spreader functions to spread the tines of the ejected bobby pin, and bobby pins mounted upon removable cardboards in said receptacle in groups of a sufficient number to fill said receptacle, said cardboards having edge portions projecting outwardly of the receptacle for removal therefrom, said fixed end wall rearward of said guide rail having a vertical slot opening through the top end thereof for receiving the bobby pins in position in the receptacle.
